UNITED STATES PATENT OFFICE.

EDWIN DE W. PEUGH, OF HURDLAND, MISSOURI.

RAILROAD-TIE.

No. 836,401.

Specification of Letters Patent.

Patented Nov. 20, 1906.

Application filed April 10, 1906. Serial No. 310,973.

To all whom it may concern:

Be it known that I, EDWIN DE W. PEUGH, a citizen of the United States, residing at Hurdland, in the county of Knox and State of Missouri, have invented certain new and useful Improvements in Railroad-Ties, of which the following is a specification.

This invention embodies novel improvements in railway-ties, the object of the invention being to secure means of the above type to obviate the necessity for use of spikes or similar fastening devices for securing rails to the ties.

The invention includes peculiar rail-attaching means for securing the rails to the tie, which securing means is of such a substantial nature as to admit, if desired, of dispensing with the usual fish-plates and bolts or fastenings customarily provided to connect meeting ends of rails.

The invention resides also in other details of construction, which will be more fully pointed out hereinafter.

For a full understanding of the invention and the merits thereof and also to acquire a knowledge of the details of construction of the means for effecting the result reference is to be had to the following description and accompanying drawings, in which—

Figure 1 is a perspective view of a railway-tie embodying the invention. Fig. 2 is a longitudinal vertical sectional view through the tie, rails in position. Fig. 3 is a transverse section on the line X X of Fig. 2. Fig. 4 is a detail view of the wedge.

Corresponding and like parts are referred to in the following description and indicated in all the views of the drawings by the same reference characters.

In the drawings the numeral 1 designates the tie, which is preferably of metallic construction and formed to provide a hollow body open at the bottom thereof and closed at the ends, as shown at 2. The body of the tie, by reason of the above-mentioned construction, is adapted to receive the ballast material of the road-bed and is consequently more substantially held in position, affording a more rigid and firm bearing than is constituted by the ordinary wooden ties, at the same time securing the necessary resiliency incident to the use of the latter.

The top of the tie is provided with rail-seats 3, transversely thereof, and at one end of each seat 3 is located an integral upwardly-projecting wing 4, adapted to engage

the rails 5 and support the same at one side, a removable clamping member 6 being provided for each of the wings 4 to coöperate therewith in supporting the rails and rigidly securing the latter to the tie. The members 6 are of peculiar formation, having the outer extremities thereof beveled, as shown at 7, to correspond with the upwardly and outwardly beveled end of the seat 3, in which each clamp member is arranged. The clamp members 6 are each provided with a lug projecting from the under side thereof and extending through a vertical opening 8 in the top of the tie. This lug 9 is transversely apertured so as to receive a wedge 10, passing transversely through suitable openings in opposite sides of the tie 1. The wedge 10 is adapted to be moved longitudinally or transversely with reference to the tie by means of a nut 11, which is screwed upon a threaded end of said wedge and bears against a spring 12, arranged between said nut and the adjacent side of the tie 1. The lug 9 of each clamp member 6 inclines downwardly toward the member 4 adjacent, and thus as the wedge 10, which coöperates with the clamp member 6, is adjusted the downward pressure exerted thereby will tend to force the engaging end of such clamp member 6 hard against the base of the rail, at the same time exerting a lateral pressure to force said clamp member against the side of the rail to facilitate the rigidity of the latter in an obvious manner. The beveled end 7 of each clamp member 6 also tends to force the clamp member laterally toward the adjacent wing 4 when the wedge 10 is being adjusted to exert a downward pressure upon such clamp member. It will be obvious that rails held in place by ties and clamping means embodying the invention are more rigidly secure than those most commonly in use at the present time, and, furthermore, the advantages of the invention whereby a structure is secured admitting of quick removal and attachment of either the rails or ties are very apparent.

Having thus described the invention, what is claimed as new is—

In combination, a railway-tie of hollow construction, rail-supporting wings projecting upwardly from the top of the tie, said tie being provided in its top with rail-seats to receive the basal portions of rails, clamp members coöperating with the wings and disposed on top of the tie, lugs projecting downwardly from the clamp members and passing

through vertical openings in the top of the tie and inclining toward the wings aforesaid, said lugs having transverse openings there-through, wedges passing transversely through the opposite sides of the tie and the openings of the lugs aforesaid, nuts screwed upon ends of the wedges to adjust the same in the manner specified, and springs inter-

posed between the nuts and the adjacent side of the tie.

In testimony whereof I affix my signature in presence of two witnesses,

EDWIN DE W. PEUGH. [L. S.]
